UNITED STATES PATENT OFFICE.

RICHARD D. FAY, OF CAMBRIDGE, AND ROBERT E. BREWER, OF BOSTON, MASSACHUSETTS.

SOUND-RADIATING DEVICE.

Original application filed April 17, 1925, Serial No. 23,917. Divided and this application filed November 16, 1925. Serial No. 69,368.

Our invention relates to sound-radiating devices particularly adapted for use with radiophone receiving systems, although capable of more general application and not limited to such use, and its object is to produce a device of this character in which the wave fronts of the radiated sound waves are initially curvilinear outwardly so that there will be substantially no directional effect.

With this object in view our invention comprises an outwardly-flaring conical tympanum having its height so related to the length of its generatrix that the wave fronts of the sound waves radiated therefrom will be initially curvilinear outwardly.

This application is a division of our application Serial No. 23,917, filed April 17, 1925.

In the drawings which accompany and form a part of this application,

Figure 1 is a longitudinal central section of a conical tympanum constructed in accordance with our invention;

Fig. 2 is a longitudinal central section of a conical tympanum hereinafter referred to in explaining the principle of our invention;

Fig. 3 is a vertical transverse section of an electrically-operated sound-radiating device provided with the conical tympanum shown in Fig. 1.

In the cone 10 shown in section in Fig. 2, the height is such that the sound waves radiated therefrom will reach the plane of the base at the same time that such waves traveling through the material of the cone from the apex 11 reach the outer periphery 12, so that the wave front is initially plane, the dotted lines 13, 13 indicating the successive positions of the wave fronts of the radiated waves. The dotted lines 14, 14 indicate approximately the wave fronts of the waves radiated from the inner surface of the cone, and it will be obvious that there will be a greater radiation of energy from the outer than from the inner surface. A sound-radiating device provided with a cone of this type will have a pronounced directional effect which is highly undesirable.

In Fig. 1 however, the cone 15 is shallower than that shown in Fig. 2, so that by the time the sound waves have travelled from the apex 16 to the outer periphery 17 through the material of the cone itself, the radiated waves will have passed beyond the

cone base and the wave front is initially curvilinear outwardly as indicated by the dotted line 18.

The sound-radiating member shown in Fig. 1 may be employed with advantage in an electromagnetically-actuated sound-radiating device such as shown in Fig. 3 in which a permanent magnet 19 having two oppositely-disposed substantially-rigid arms adjustable by the screw 20 support two oppositely-disposed and substantially parallel, flexible permeable armature-supporting members 21, 21 such as relatively stiff flexible discs, each clamped between a pair of permeable rings 22, 22, arranged on the opposite faces of each disc near the periphery thereof, by screw or bolts (not shown) and also by the bolt 24 and nut 25. The said discs are secured to the permanent magnet by the bolts 23, 23 which assist in clamping the discs between their respective supporting rings. A bolt 24 of non-permeable metal and the nuts 25, 25 serve not only to grip the discs between the rings 22, but also to hold said discs rigidly spaced apart at the portion of their circumference farthest away from their points of attachment to the permanent magnet.

Two oppositely-directed tubular armatures 26, 26 are supported on the discs 21, 21, respectively, at the centers thereof. Supported by the armatures in any suitable manner are the oppositely-disposed sound-radiating members 15, 15 which may be of parchment, fibre, or any other suitable material, said members being conical and having their peripheral portions slightly bent back as shown at 27. Each conical tympanum or sound-radiating member is supported solely at its apex on its actuating armature by means of a sleeve 28 which passes through the apex and is threaded to the outwardly-projecting end of the armature, said sleeve being formed integral with a conical portion 29 to which the tympanum may be attached by gluing or otherwise.

A magnetizing coil 30 is arranged in the space between the discs and is concentric with the armatures, said coil being wound on an insulating spool 31 supported in the present instance in the rabbeted inner peripheries of the adjacent rings 22.

It will be understood of course that our invention is not limited to use with the apparatus illustrated in Fig. 3 which is shown merely for completeness of disclosure.

Having thus described an illustrative embodiment of our invention without however limiting the same thereto, what we claim and desire to secure by Letters Patent is:—

10. 1. In a sound-radiating device, an outwardly flaring conical tympanum having its height so related to the length of its generatrix that the wave fronts of the sound waves radiated therefrom will be initially
- 15 curvilinear outwardly.

2. In a sound-radiating device, a conical tympanum having its height so related to the length of its generatrix that the time required for a sound wave radiated therefrom to travel from its apex to the plane of ²⁰ its base is less than the time required for a sound wave to travel through the material of said tympanum from its apex to the periphery of its base.

In testimony whereof, we have hereunto ²⁵ subscribed our names this 14th day of November, 1925.

RICHARD D. FAY.
ROBERT E. BREWER.
